FACEPLATE FOR A BUILT-IN VACUUM SYSTEM

Felix H. Tevis, South Pasadena, Calif., assignor to Tevis-Campbell Corporation, South Pasadena, Calif.

Filed Mar. 22, 1972, Ser. No. 237,241

Term of patent 14 years

Int. Cl. D8—09

U.S. Cl. D8—179

FIG. 1

FIG. 2

FIG. 3

FIG. 1 is a front view of my faceplate for a built-in vacuum system showing my new design.

FIG. 2 is a side view of FIG. 1.

FIG. 3 is a top view of FIG. 1.

I claim:

The ornamental design for a faceplate for a built-in vacuum system, as shown and described.
